(57) **CLAIM**

The ornamental design for a soft-sided insulated container, as shown and described.

DESCRIPTION

FIG. 1 is a front side perspective view of our soft-sided insulated container in the expanded configuration;

FIG. 2 is a rear elevation view thereof;

FIG. 3 is a front elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front side perspective view of our soft-sided insulated container in the collapsed configuration;

FIG. 9 is a rear elevation view thereof;

FIG. 10 is a front elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The broken lines represent portions of the design that form no part of the claim.
